UNITED STATES PATENT OFFICE.

LOUIS STOCKSTROM, OF ST. LOUIS, MISSOURI, ASSIGNOR TO AMERICAN STOVE COMPANY,
OF ST. LOUIS, MISSOURI, A CORPORATION OF NEW JERSEY.

WATER-HEATER.

No. 914,200.

Specification of Letters Patent.

Patented March 2, 1909.

Application filed January 22, 1906. Serial No. 297,317.

To all whom it may concern:

Be it known that I, LOUIS STOCKSTROM, a citizen of the United States, residing at St. Louis, in the State of Missouri, have invented 5 a certain new and useful Improvement in Water-Heaters, of which the following is a specification, reference being had therein to the accompanying drawing.

This invention relates to an improvement 10 in water heaters, and has for its object the providing of a vertically movable shell or casing for the heater and burner, and means for moving the shell vertically, whereby direct access to the main burner is provided 15 for lighting purposes.

In the accompanying drawing, Figure 1, is a perspective view of a water heater involving my invention, the shell of the water heater being shown raised in solid lines for 20 lighting purposes, and lowered in dotted lines to its operative position. Fig. 2, is a sectional perspective view, the shell being shown in central section.

Referring now to the drawing, 1 indicates 25 the usual hot water tank or boiler. This hot water tank or boiler is connected with the water heater 2 through the medium of the connections 3, 4 and 5.

The interior construction of the water 30 heater 7 may be such as that shown in Fig. 2, or any other desired form. It will be observed, however, that in the form of water heater to be used with the surrounding shell 6, the water heater to a large extent 35 obstructs the shell, so that the heat from the burner will be more effective for heating the water. This is true in all forms of water heaters of the type here shown.

My present invention pertains to the vertically 40 movable casing or shell 6, which is here shown with its lower portion 7 enlarged and surrounding the main gas burner 8. In the position shown in full lines, direct access is permitted to the main burner 8 for lighting 45 purposes, the flow of gas to the burner being controlled by any suitable valve 9.

Projecting from the interior portion of the water heater is a flue or tube 10, and secured to this flue or tube 10 is a flange 11. When 50 the vertically movable casing or shell 6 is in its normal and lower position (as shown in dotted lines) the shell or casing 6 is supported by engagement with the flange 11. By pressing down upon an intermediately 55 pivoted lever 12 the casing or shell 6 is raised

by means of a link 14 which connects the casing or shell with one end of the intermediately pivoted lever 12.

In water heaters of this character, the outer casing 6 is stationary and incloses the main burner, and there is an auxiliary burner which is to be lighted by the operator before turning on the main burner. With the casing or shell in its immovable position surrounding the main burner, it has been found 60 that frequently servants and others intrusted with the lighting of these heaters, first turn on the main burner and then light the sub-burner, which as a consequence causes an explosion within the casing, doing more or 65 less damage. The liability of the foregoing result is exaggerated in water heaters of this type by reason of the fact that the water heater very materially obstructs the flow of the gas through the shell 6, so that the gas is 70 retained within the shell, and where the shell is stationary, as heretofore, to first turn on the gas and then light it in the manner previously stated, an explosion is the result. By providing a movable casing or shell which 75 surrounds the burner, and leaving off the sub or auxiliary lighter, the operator is required to lift the portion surrounding the main burner and to have direct access to the main burner for lighting purposes. - 85

In the type of heater to which this invention relates, when the shell 6 is down and the gas is turned on, there is considerable draft through the shell and the gas escaping from the burner is quickly carried up into the 90 shell and if the burner is then lighted, an explosion is likely to occur by reason of the expansion of the ignited gas in the shell. When, however, the shell 6 is raised the draft through the shell is thereby destroyed, 95 and by reason of the space then existing between the lower end of the shell and the burner, enough of the gas escapes around and outside of the shell to prevent an ignitable mixture being formed in the shell, and this 100 result has been fully demonstrated by the practical every day use of the heater for domestic and similar purposes.

Having thus described my invention, what I claim and desire to secure by Letters Patent, is:—

1. A water heater comprising a water container, a burner below said container, and a vertically-movable shell normally surrounding the water container and burner, and

- means for moving the shell vertically above the burner to expose it for lighting and to cause a large proportion of the unlighted gas from the burner to pass outside of the shell
- 5 and thus prevent the formation of an ignitable mixture within the shell prior to lighting the burner, for the purpose described.
2. A water heater comprising a vertically-movable shell having open ends, a stationary
- 10 member for closing its upper end, a burner at its lower end, a water container within the

shell, and means for lifting the shell and thereby permitting the gas from the burner to escape outside of and through the said shell prior to lighting the burner.

15

In testimony whereof I affix my signature in presence of two witnesses.

LOUIS STOCKSTROM.
